UNITED STATES PATENT OFFICE.

JOSEPH LE CONTE DAVIS, OF PITTSBURGH, PENNSYLVANIA, ASSIGNEE, BY MESNE ASSIGNMENTS, TO WESTINGHOUSE ELECTRIC & MANUFACTURING COMPANY, OF EAST PITTSBURGH, PENNSYLVANIA, A CORPORATION OF PENNSYLVANIA.

LOCOMOTIVE.

1,138,638.

Specification of Letters Patent. Patented May 11, 1915.

Application filed January 10, 1908. Serial No. 410,228.

To all whom it may concern:

Be it known that I, JOSEPH LE CONTE DAVIS, a citizen of the United States, and a resident of Pittsburgh, in the county of Allegheny and State of Pennsylvania, have invented a new and useful Improvement in Locomotives, of which the following is a specification.

My invention relates to electric locomotives and to driving motors therefor, and it has for its object to provide a locomotive and driving motors of extreme simplicity and compactness of construction.

My invention is illustrated in the accompanying drawings, Figure 1 of which is a view, in side elevation, of a locomotive constructed in accordance therewith. Fig. 1^a is a diagrammatic side elevation of the motor field magnet frame and armatures. Fig. 2 is a diagrammatic view of the circuit connections of the locomotive. Fig. 3 is a top plan view of the locomotive. Fig. 4 is a vertical sectional view on the line IV—IV of Fig. 1, and Fig. 5 is a perspective view of the field magnet frame of the locomotive.

Mounted upon and rigidly secured to axles 1 and 2 that carry the driving wheels of the locomotive are armatures 3 and 4 of the propelling motors. The motors are provided with a common field magnet frame 5 comprising three polar projections 6, 7, and 8 having long concave side faces between which the armatures 3 and 4 are located, the lower portions 9, 10, and 11 of the polar projections being detachable in order to permit of ready insertion and removal of the armatures into and from their operative positions. The middle polar projection 7 is provided with a winding comprising two sections 12 and 13 that may be connected either in series or in parallel relation in order to obtain variable speeds of operation by means of any suitable controller 14.

The field magnet frame 5 is supported by means of a truck frame comprising two side plates 15 and 16, to which the field magnet frame 5 is secured by means of bolts 17, and two end pieces 18 and 19 adapted to secure the side plates 15 and 16 together and to accommodate a motorman or other operator. The truck frame is resiliently supported upon journal bearings 20 by means of helical compression springs 21, and, in

order to permit of a slight amount of relative movement between the armatures and the polar projections of the motors, the curvature of the concave faces of the polar projections is made such that there is normally a wider air-gap between the upper side portions of the armatures and the adjacent portions of the pole faces than between the lower side portions of the armatures and the adjacent lower portions of the pole faces. The magnetic attraction between the lower portions of the polar projections and the lower side portions of the armatures therefore normally tends to raise the truck frame and the attached parts and to thereby relieve the springs 21 of a portion of the weight thereof, this result being effected by reason of the dimensions, form and location of the pole pieces as well as by the difference in width of certain portions of the air gaps, as above set forth.

I claim as my invention:

1. An electric locomotive having a short wheel base and comprising a horizontally disposed magnetizable yoke provided with three integral downwardly projecting pole pieces having free ends, armatures rotatably mounted between the middle and outer pole pieces and a winding surrounding the middle pole piece and disposed above the armatures.

2. An electric locomotive having a short wheel base and comprising a horizontally disposed magnetizable yoke provided with three downwardly projecting integral pole pieces having free ends, armatures rotatably mounted between the middle and outer pole pieces, a two-part concentric winding surrounding the middle pole piece above said armatures and means for connecting the parts of the field magnet winding in either series or parallel relation.

3. An electric locomotive having a short wheel base comprising a substantially horizontal yoke provided with three downwardly projecting integral pole pieces having detachable free ends, a winding surrounding the upper portion of the middle pole piece, and armatures rotatably mounted between the middle and outer pole pieces.

4. The combination with a pair of driving axles, and armatures carried thereby, of side frames and a field magnet frame se-

cured thereto and resiliently supported upon the axles and comprising a substantially horizontal yoke and three downwardly projecting pole pieces having unconnected lower ends and provided with long concave side faces between which the armatures are located.

5. The combination with a pair of driving axles, and armatures carried thereby, of a field magnet frame resiliently supported upon the axles and comprising a substantially horizontal yoke and three downwardly projecting pole pieces having unconnected lower ends and provided with long concave 10 side faces between which the armatures are located, and a field magnet winding surrounding the middle pole piece above said armatures.

6. In a locomotive, the combination with 20 side frames and a unitary magnetizable yoke secured thereto to constitute the locomotive body and embodying three integral downwardly projecting pole pieces, said yoke and said pole pieces being disposed within the 25 height of the side frames, of armatures rotatably mounted between the middle and outer pole pieces.

7. In a locomotive having a short wheel base, the combination with side frames and 30 a unitary magnetizable yoke secured thereto to constitute the locomotive body and embodying three integral downwardly projecting pole pieces of less width than the width of the yoke, said yoke and associated pole 35 pieces being disposed within the height of the side frames, of armatures rotatably mounted between the middle and outer pole pieces and concentric field magnet coils sur-

rounding the upper portion of said middle pole pieces.

8. In a mining locomotive having a wheel base substantially equal to the diameter of the wheels, the combination with a pair of driving axles having driving wheels, armatures mounted upon said axles and a locomotive body resiliently supported by said axles and comprising a magnetizable horizontal yoke and side frames secured to the sides thereof, said yoke being provided with 45 downwardly projecting integral pole pieces disposed within the height of the side frames, of a plurality of separated concentric field magnet coils surrounding the middle pole pieces above said armatures and beneath said yoke.

9. The combination with a pair of driving axles, and armatures mounted thereon, of a field magnet frame resiliently supported upon the axles and comprising a substantially horizontal yoke and three downwardly projecting pole pieces having long concave side faces between which the armatures are located, the curvature of the pole faces being such that the air gaps between the armatures and the lower portions of the 60 pole faces are narrower than those between the armatures and the upper portions of said faces.

In testimony whereof, I have hereunto subscribed my name this 27th day of Dec., 70 1907.

JOSEPH LE CONTE DAVIS.
